United States Patent Office
Patents are granted upon inventions and discoveries
which are useful or important, and which are
new, and which are not obvious to others, and
which are not within the scope of prior art.
The scope of prior art includes any invention or
discovery which is known to others, or which
is described in a publication, or which
is used in a public way, or which is
otherwise available to the public.
The scope of prior art includes any invention or
discovery which is known to others, or which
is described in a publication, or which
is used in a public way, or which
is otherwise available to the public.

VENTILATOR FOR BUILDINGS
John H. Klunder, Chicago, Ill.
Application June 25, 1940, Serial No. 342,240
3 Claims. (Cl. 98—37)

This invention relates to ventilators for buildings, and more specifically to ventilators adapted to become part of the outside wall, and designed primarily to ventilate the air between the ceiling and the roof.

Ventilators in use at the present time for the purpose of ventilating the dead air space between the ceiling and a relatively horizontal roof have certain formidable objections; snow, rain and the elements generally, will enter the ventilator and while the amount of moisture that will thus enter might appear to be limited, it will, nevertheless, be wholly sufficient to cause disintegration of certain parts of the interior. Among such ventilators in use at the present time are horizontal pipes or openings, or a plurality of louvers, in both of which types of ventilators some step in the direction of preventing a portion of the rain and snow from entering is effected, but for all practical purposes such devices as are on the market at the present time, including the two types alluded to above, large amounts of water and rain still enter and, therefore, the need of an invention which will prevent the same is highly desirable.

It is, therefore, an object of my invention to provide a ventilator adapted to form a part of a wall which will prevent any rain, sleet, snow or other elements from obtaining ingress to the interior of the building.

A further object of my invention is to construct a ventilator having utilities not found in any ventilators at the present time, and which will be very inexpensive and economical to manufacture.

A further object of my invention is to provide a ventilator which will not permit direct torrents of air, such as storms and tornadoes, from having direct and non-circumlocuous access to the interior of the building, and to perform this object without the intervention of dampers or valves, it heretofore having been common for inventions to include such a damper or valve in order to safeguard against storms and the like.

These and other objects of my invention will appear from an inspection of the drawing, in which

Figure 1 is a cross-sectional, elevational view of my invention, showing the same forming a part of a wall;

Figure 2 is a cross-sectional, plan view taken on the lines 2—2 of Figure 1 looking in the direction of the arrows; and

Figure 3 is a perspective view of my improved ventilator.

The several figures similar portions are designated by similar reference characters in which 1 is a vertical wall above the ventilator, 2 the roof of the building, 3 the supports for the roof, 4 the dead air space between the roof and ceiling, 5 the vertical wall beneath the ventilator, 6 the plaster forming the ceiling of the room, 7 the plaster laths, 8 is the top horizontal portion of my ventilator, 9 the vertical portion of the ventilator, 10 a hood extending outwardly and downwardly from the top portion 9, 11 is the bottom extension of 10, 12 is the horizontal bottom side of the ventilator, 13 is a screen extending from the diagonal portion 10 of the hood to the bottom part 12 of the ventilator, said screen being made contiguous at 14 by means of soldering and the like. 15 is the end portion of the hood, 16 is the bottom edge thereof, 17 is the edge of the hood parallel with the wall of the building, 18 and 19 are the two vertical ends of the ventilator, and 20 is the open space of the ventilator formed by the ends 18 and 19, and the bottom 12 and top 8 of the ventilator.

My improved ventilator in the form of a rectangular box having a relatively long hood extending exteriorly and downwardly from one edge of said box, is set within a wall with the bricks or mortar above, below and at the sides of said ventilator. It may be constructed of any inexpensive metal and it is desirable that a plurality of ventilators be installed for each building or each area of dead air space to be ventilated. For a relatively small area two ventilators, preferably staggered so as to get a diagonal ventilation across the dead air space, may be sufficient, although for large buildings the number of ventilators may be increased as desired. The outwardly and downwardly projecting hood member 10 provides an inlet for air into the ventilator which inlet is preferably provided with a screen 13 so as to exclude dirt and other undesirable elements. For the purpose of this application the inlet as implied in the preceding sentence is defined to be that horizontal space formed by the diagonal hood 10 and the bottom part 12 of the ventilator, and which is substantially coextensive with the screen 13 covering the same. The lower portion 11 of the hood 10 extends relatively far below the opening covered by the screen 13 and thus definitely and positively prevents any rain, snow or sleet from entering the inlet. The hood designated by 10 and the extreme lower portion thereof by 11, is provided with vertical side members 15 which prevent rain or snow from entering at the inlet screen 13. The

air, therefore, entering the ventilator takes an upward course from beneath the edges 16 and 17 of the hood, forcing it upward as indicated by the arrows shown in Figures 1 and 3 and enters the interior of the ventilator. The ventilator being hollow and having its entire rear side 20 exposed, serves as an unobstructed passageway of the air into the dead air space 4. With my device the dead air space between the ceiling and the roof is obviated and experience has shown that unless there is some ventilation for this dead air space, condensation will occur in the plaster or the ceiling of the room immediately adjacent to the dead air space and, therefore, ventilating means are quite essential. If the heretofore known means are provided for obviating the dead air space, as has heretofore been the case by means of ventilators which permit the entrance of rain, sleet or snow, equally undesirable and disintegrating factors will result by reason of the rain and moisture working its way through the ceiling.

My invention is not to be understood as restricted to the details set forth, since these may be modified within the scope of the appended claims, without departing from the spirit and scope of the invention.

Having thus described the invention, what I claim as new and desire to secure by Letters Patent is:

1. In a ventilator system, the combination of a wall having a transverse opening, an air conduit

disposed in said opening, said air conduit comprising a tubular structure having an open end in communication with the interior of the building, and having the opposite end substantially in alignment with the outer edge of the wall, the said last mentioned end provided with a hood extending outwardly and downwardly well below the bottom of said tubular structure, and a screen extending from the bottom of said air conduit in substantially horizontal plane to said hood whereby air is permitted to pass through said conduit without permitting foreign matter to pass therethrough.

2. A ventilator adapted to form a part of an outside wall comprising a tubular member, one end of said member being open and the other end provided with a downwardly and outwardly extending hood, an air inlet space provided between the said hood and the bottom of said member, the said hood extending a greater distance downwardly than the width of the said inlet space.

3. A ventilator adapted to be mounted in an opening in a wall for ventilating a dead air space comprising an open-ended tubular member, a hood extending outwardly and downwardly providing an air space inlet between said hood and the bottom wall of said member, the length of said hood from the bottom edge thereof to said inlet being greater than the width of said inlet, whereby snow, sleet and rain are prevented from entering said inlet.

JOHN H. KLUNDER.
